UNITED STATES PATENT OFFICE.

JOHN F. BITTLE, OF LISBON, IOWA.

WICK-HOLDER FOR OIL-STOVES.

1,082,395.

Specification of Letters Patent. Patented Dec. 23, 1913.

Application filed October 8, 1913. Serial No. 793,140.

To all whom it may concern:

Be it known that I, JOHN F. BITTLE, a citizen of the United States, and a resident of Lisbon, in the county of Linn and State 5 of Iowa, have invented a new and Improved Wick-Holder for Oil-Stoves, of which the following is a full, clear, and exact description.

My invention relates to a means for holding tubular wicks, and it especially relates 10 to the holders for the tubular wicks of oil stoves.

The common form of a wick holder consists of a perforated cylindrical shell, the 15 lower end of which is inturned and forms a binding over the wick, at the inside of the holder. As the wick in the old holder referred to is permanently secured in place, it cannot be renewed, so that a new holder 20 is required to renew the wick. In my invention a novel clamping means is provided in connection with the holder, to detachably engage the wick, so that the remnant of a burned wick may be readily removed and 25 a new wick secured to the holder.

The invention will be particularly explained in the specific description following.

Reference is to be had to the accompanying drawings forming a part of this specification, in which similar characters of reference indicate corresponding parts in both views.

Figure 1 is a bottom view of a wick holder 35 embodying my invention, the view including a tubular wick; and Fig. 2 is a vertical section on the line 2—2 of Fig. 1.

In forming the wick holder in accordance with my invention, a suitable shell 10 is 40 provided, which may be of known form, for receiving therein a tubular wick, indicated by the letter A. In connection with the shell 10, I employ novel clamps 11, which are hingedly secured to the shell 10, at the 45 lower edge of the latter, and extend upwardly within the wick A. I have shown three of the clamps 11, and preferably, each is of tapering form, providing a comparatively broad base for the formation of a 50 hinge element thereon, which consists of a

member 12 desirably of less width than the base of the body of the clamp 11, the said member being bent around a wire ring 13, which is secured to the lower end of the shell 10 by turning the lower edge 14 of the 55 shell inwardly over the said ring. The in-turned portion 14 is cut away as at 14^a, to expose portions of the ring 13 and accommodate the clamp members 11.

On the side edges of the clamps 11, teeth 60 or spurs 15 are produced and bent laterally at an angle to the plane of the clamp, to enter the material of the wick A, as indicated by dotted lines at the left of Fig. 2. To release a wick from the holder, or to 65 adjust the clamps to receive a wick, said clamps are rocked on their hinges 12 away from their clamped position, which is indicated by dotted lines at the left of Fig. 1, to a position at an angle to the shell, as indicated in full lines in both figures.

It will be obvious that with my improved holder, the remnant of a wick can be readily detached and a new wick as readily secured in place, thereby saving the expense of 75 a new holder.

Having thus described my invention, I claim as new, and desire to secure by Letters Patent:

1. A wick holder, comprising a shell to 80 receive the wick, and inner movable clamp members at the lower end of the holder adapted to detachably engage the lower end of a wick, said members projecting upwardly around the lower edge of the shell, 85 at the interior, and spaced from the shell to accommodate the wick between the said members and the inner surface of the shell.

2. A wick holder, comprising a shell, and clamp means hinged to the lower end of the 90 shell at the inside, and spaced from the shell to accommodate a wick.

3. The herein-described wick holder, comprising a shell having the lower edge thereof in-turned, a ring held by the in-turned 95 edge of the shell, the said in-turned edge being removed at intervals exposing portions of the ring, and clamps within the shell and spaced therefrom, the said clamps having teeth to engage the wick, and provided at 100

the lower ends with hinge members turned about the exposed portions of the ring.

4. A wick holder, comprising a shell, and clamps disposed within the shell and hinged to the shell, at the lower end thereof, the said clamps tapering from the lower end upwardly and having teeth at opposite side edges thereof, to engage a wick.

In testimony whereof I have signed my name to this specification in the presence of 10 two subscribing witnesses.

JOHN F. BITTLE.
